UNITED STATES PATENT OFFICE.

MAX PEINLICH, OF WHITE PLAINS, NEW YORK, ASSIGNOR TO COLUMBIA LIGHTING FIXTURE CO. INC., OF NEW YORK, N. Y., A CORPORATION OF NEW YORK.

DESIGN FOR A CHANDELIER OR THE LIKE.

Application filed March 12, 1927. Serial No. 21,120. Term of patent 3½ years.

To all whom it may concern:

Be it known that I, MAX PEINLICH, a citizen of the United States, residing in White Plains, county of Westchester, and State of New York, have invented a new, original, and ornamental Design for a Chandelier or the like, as shown, of which the following is a specification, reference being had to the accompanying drawing, forming part hereof, in which

The figure is a perspective view of my chandelier showing my design.

The arms of the chandelier are adapted to support lights, preferably of the upright type, as shown by the dotted lines in the drawing, it being understood, however, that the customary inverted lights may be used.

I claim:

The ornamental design for a chandelier or the like, as shown and described.

MAX PEINLICH.
